UNITED STATES PATENT OFFICE.

PAUL S. EVANS, OF MOBILE, ALABAMA, ASSIGNOR TO MOBILE STEEL COMPANY, OF MOBILE, ALABAMA, A CORPORATION.

SYRUP-EVAPORATOR.

1,251,763.

Specification of Letters Patent.

Patented Jan. 1, 1918.

Application filed April 21, 1917. Serial No. 163,596.

To all whom it may concern:

Be it known that I, PAUL S. EVANS, citizen of the United States, residing at Mobile, in the county of Mobile and State of Alabama, have invented certain new and useful Improvements in Syrup-Evaporators, of which the following is a specification.

My present invention has to do with syrup evaporators. It consists in the peculiar construction, novel combination and adaptation and relative arrangement of parts, as hereinafter described and claimed, whereby the evaporator is provided with a solid, durable and liquid-tight bottom wall, and the transverse partition walls are fixedly attached to said bottom wall and strongly maintained in position without the employment of solder or any other element liable to be affected by fire or heat.

20 In the accompanying drawings which are hereby made a part hereof:

Figure 1 is a longitudinal vertical section illustrating the evaporator constituting the best practical embodiment of my invention 25 that I have as yet devised.

Fig. 2 is a plan view of the same.

Fig. 3 is a perspective, on an enlarged scale, showing the relative arrangement of the bottom wall and one partition wall preceding to the application of pressure to clamp the engaged parts of said walls and fix the same with respect to each other.

Fig. 4 is an enlarged detail section showing the bottom wall and one partition wall 35 as they appear subsequently to the application of pressure and the fixing of the partition wall to the bottom wall.

Similar numerals of reference designate corresponding parts in all of the views of 40 the drawings.

As shown in Figs. 1 and 2, my novel evaporator comprises, among other parts, two upright wooden side walls 1 and 2. These side walls 1 and 2 are arranged in parallel relation, and the wall 1 is provided, adjacent to one of its ends, with a transverse outlet aperture 3 for the discharge of syrup from the evaporator.

50 Embedded along its side edges in the opposed side walls 1 and 2 is the sheet metal bottom wall 4, and carried by the said bottom wall 4 and each embedded at one end in one wooden side wall are the comparatively high transverse partition walls 5 and 55 the low or shallow transverse partition walls

6. These walls 5 and 6 are alternately secured to opposite side walls, each wall 5 and 6 extending from one side wall and having its free end spaced from the other side wall in order to cause the syrup to take a tortuous course in passing from the right-hand end of the evaporator toward the discharge outlet before referred to, as indicated by the arrows in Fig. 2. Aside from differences 60 in height the transverse partition walls 5 and 6 are identical in construction and are similarly fixed with respect to the bottom wall 4, and therefore a detailed description of the wall 5 and the adjacent portion of the wall 4 shown in Figs. 3 and 4 will suffice to impart a definite understanding of all. 65

For the reception of the said wall 5, the bottom wall 4 is provided with the opposite folds 7 and the throat 8 between the folds. The wall 5 is formed of a sheet of metal bent 70 on itself to constitute an upstanding portion, and the said sheet of metal is provided at the base of the upstanding portions with flanges 9. These flanges 9 are sheathed, preferably by endwise movement of the wall 75 5, in the folds 7 and the base of the upstanding portion is disposed in the throat 8. The opposed portions of the folds 7 and the flanges 9 are then subjected to pressure to tightly clamp the flanges between the folds 80 85 whereupon the partition wall will be fixed in and to the bottom wall and a liquid tight joint will be provided between the two, and this without the employment of solder or any other extraneous means. 90

It will be observed in this connection that the upstanding portion of the wall 5 is strongly clamped and held between the upper opposed bights of the folds 7, and the said wall 5 is effectually held at both sides 95 thereof against movement in the direction of its thickness; also, that the sheathing capacity of the folds 7 permits of the wall 5 being expeditiously and easily positioned, relative to the bottom wall before the opposed portions of the folds 7 and flanges 9 are subjected to pressure as described. 100

In assembling the parts of my novel evaporator, the end portions of the bottom wall 4 are bent upwardly to form end walls 10, 105 the upper edges of which are beaded as indicated by 11, and the side edges of the bottom wall, throughout the length thereof are tightly seated in grooves provided in the inner sides of the side walls, while one end of 110

each transverse wall is tightly seated in other grooves provided in the inner side of one side wall. The described fixing of the bottom walls and the transverse partition walls 5 to the side walls is also accomplished without the employment of extraneous means, and this also contributes materially to the simplicity, inexpensiveness and durability of the evaporator.

- 10 Having described my invention, what I claim and desire to secure by Letters Patent is:

In an evaporator, the combination of a sheet-metal bottom wall having at intervals of its length pairs of opposite folds and a throat between the folds of each pair, and transverse partition walls carried by the bottom wall, each of said partition walls being formed of a single piece of sheet-metal

folded upon itself to form an upstanding portion and each having oppositely reaching flanges at the base of its upstanding portion sheathed in opposite folds of the bottom wall, and the folds of the bottom wall and the base flanges of the partition walls 25 being clamped together, whereby the upstanding portions of the partition walls are strongly clamped and held between the upper opposed bights of the bottom wall folds and the partition walls are held at both sides 30 thereof against movement in the direction of the length of the bottom wall.

In testimony whereof I affix my signature in presence of two witnesses.

PAUL S. EVANS.

Witnesses:

JOHN R. COWLEY,
JAS. A. COWLEY.
